United States Patent Office

Des. 207,900
Patented June 13, 1967

207,900

HELMET

Frederick W. Feldmann, Dover, Del., and Robert G. Koch,
Blackwood, N.J., assignors to ILC Industries, Inc.,
Dover, Del., a corporation of Delaware

Filed Sept. 6, 1966, Ser. No. 3,726

Term of patent 14 years

(Cl. D2—232)

Fig. 1

Fig. 2

Fig. 3

Fig. 4

FIG. 5

FIGURES 1 through 4 are respectively side, top, front and rear views of a helmet showing our new design; and FIGURE 5 is a bottom perspective view thereof, the strap being broken away for convenience of illustration.

We claim:

The ornamental design for a helmet, as shown and described.
